UNITED STATES PATENT OFFICE.

HOMER J. DANA, OF CONNELL, WASHINGTON.

HYDRAULIC STUMP SPLITTER AND PULLER.

1,330,687.

Specification of Letters Patent. Patented Feb. 10, 1920.

Application filed December 7, 1917. Serial No. 206,044.

To all whom it may concern:

Be it known that I, HOMER J. DANA, a citizen of the United States, residing at Connell, in the county of Franklin and State 5 of Washington, have invented new and useful Improvements in Hydraulic Stump Splitters and Pullers, of which the following is a specification.

This invention relates to hydraulic stump splitters and pullers or extractors the object 10 in view being to provide a complete self-propelled machine which may be driven to and from the place of operation and which may be utilized efficiently to split stumps 15 and subsequently pull or extract the same, the several sets of mechanisms being under the control of a single operator.

The principal object of the invention is to produce a novel form of hydraulic 20 mechanism embodying in combination with a piston and cylinder, a compensation chamber having a novel relation thereto and serving to eliminate all danger of excessive pressure of water or other liquid in the cylinder, making it practically impossible for 25 a careless operator to wreck the cylinder.

A further object is to mount the hydraulic mechanism on a self-propelled truck and combine therewith means for splitting 30 stumps and also means for pulling or extracting the same either before or after being split.

A further object of the invention is to provide a novel construction of grip to be 35 used in conjunction with the cable and windlass during the operation of extracting stumps and the like. In the operations of splitting and extracting stumps and the like, the power of the engine is utilized, the engine 40 being for the time uncoupled from the driving gear of the vehicle.

With the above and other objects in view, the invention consists in the novel construction, combination and arrangement of 45 parts, herein fully described, illustrated and claimed.

In the accompanying drawings:—

Figure 1 is a plan view of the improved hydraulic stump splitter and puller.

Fig. 2 is a side elevation of the same with the parts in section.

Fig. 3 is a vertical transverse section on the line 3—3 of Fig. 2.

Fig. 4 is a vertical transverse section on 55 the line 4—4 of Fig. 2.

Fig. 5 is a diametrical section through the

hydraulic cylinder illustrating the construction of the heads thereof.

Fig. 6 is a fragmentary plan view showing the means for supporting one end of 60 the hydraulic cylinder.

Fig. 7 is a fragmentary side elevation showing the pump, the hydraulic cylinder, and the connections between the same including the valve. 65

Fig. 8 is a similar view showing the reversed position of the valve.

Fig. 9 is a side elevation of the cable grip.

Fig. 10 is a vertical longitudinal section of the same. 70

Fig. 11 is a plan view thereof. 75
The vehicle or truck comprises a substantially rectangular frame comprising the longitudinal side bars 1 of I-beam formation connected in fixed relation to each other by a plurality of cross bars as shown in Fig. 1. 2 designates the rear axle, 3 the front axle, 4 the driving or traction wheels and 5 the front or steering wheels.

Mounted upon the truck frame about centrally thereof is an engine 6, such as an internal combustion engine, the same being supported upon cross cars 7 and 8 of the truck frame. 9 designates the flywheel of the engine connected by a clutch, in accordance with motor vehicle practice, with a longitudinal shaft 10 journaled in bearings on cross bars 11 and 12 of the frame. Parallel to the shaft 10 is a countershaft 13 carrying gears 14, 15 and 16 for low speed, 90 high speed and reverse, the gears 17 and 18 being movable into and out of mesh with gears 14 and 15 on the shaft 10, and the gear 16 meshing indirectly through another gear with a gear 19 on the shaft 10. The 95 gearing corresponds with the sliding gear transmission now employed in motor vehicle practice, any suitable or usual means under the control of the driver being provided for shifting the gears to obtain high or 100 low speed and reverse.

Extending rearwardly beyond the countershaft 13, and in a plane parallel thereto is a second countershaft 20 connected to and driven by the shaft 13 by means of gears 21 105 and 22. The shaft 20 is provided with a pump controlling clutch 23 and at its rear end the shaft 20 has fast thereon a bevel gear 24 which meshes with a bevel gear 25 on a pump driving shaft 26. The countershaft 13 extends in rear of the gears 21 and 22 and has fast thereon a bevel pinion 27 110

which meshes with and drives a large bevel gear 28 on a sectional transverse shaft 29, the sections of which are connected by differential gearing 30. On the opposite ends 5 of the shaft 29 there are pinions 31 which mesh with gears 32 housed within recesses 33 in the inner faces of the driving or traction wheels 4. A clutch 34 associated with the countershaft 13 enables the engine 6 to 10 be uncoupled from the driving mechanism of the vehicle so that the power of said engine may be utilized for splitting and extracting stumps.

Arranged under the frame of the truck is 15 a longitudinally extending hydraulic cylinder 35 which, in connection with a pump 36 is best illustrated in Figs. 5, 7 and 8. 36' designates the hydraulic cylinder proper which is provided at both ends thereof with 20 a double or two-piece head. The inner member 37 of the head is formed with a central opening 38 to receive the adjacent end of the cylinder 36' and the outer member 39 of the head is formed with a rabbet 25 40 to receive a corresponding enlargement 41 on the meeting face of the member 37. This provides a liquid tight joint between the sections of the head. At one end, the outer member 39 of the cylinder head is 30 provided with a stuffing box 42 through which reciprocates the rod 43 of a piston 44 mounted for back and forth movement in the cylinder 36'. Located adjacent to the cylinder 36' is a compensation cylinder or 35 chamber 45 which extends parallel to the cylinder 36'. From the pump 36, a pipe 46 containing a check valve 47 extends to a port 48 in one head of the cylinder 36'. Another pipe 49 containing a check valve 50 extends from the pump 36 to a port 51 in the other head of the cylinder. A pipe 52 extends from one end of the compensation chamber or cylinder 45 to the pipe 46. The pipes 46 and 49 are connected to the casing 45 of a two-way valve 53 which in one position permits the liquid to flow in one direction and which, when given a quarter turn, directs the liquid in the opposite direction. As shown in Fig. 7, the liquid forced by the 50 pump 36 is flowing in the direction indicated by the arrows, while Fig. 8 illustrates the other position of the valve when the liquid is flowing in the reverse direction. The cylinder 36' also has release cocks 54 55 connected with the opposite heads thereof as shown in Fig. 7.

The means for supporting the cylinder 36' in relation to the frame of the truck is illustrated in Fig. 6 in which it will be 60 seen that a cross bar 55 extends between the side bars 1 of the frame and is fixedly secured thereto by fastening means 56. The central portion of the cross bar 55 has a semi-circular depressed portion 57 forming 65 a receiving saddle for the adjacent head 39

of the cylinder 36' and said cylinder head has supporting lugs 39' which rest on the frame.

Secured fixedly to the projecting end of a piston or plunger rod 43 is a wedge shaped 70 stump splitting head 59 having a plurality of holes 60 extending vertically therethrough to receive the fastening bolts of the cable grip. The cable grip, which is illustrated in Figs. 9, 10 and 11, comprises 75 a pair of supporting arms 61 which are fastened by bolts 62 to the stump splitting head 59, the bolts 62 being inserted through the holes 60. The arms 61 diverge from their point of attachment to head 59 and the extremities thereof are connected by one or more cross yokes or braces 63. The grip embodies a head 64 formed with recesses to admit of a limited movement of a pair of cable gripping jaws 65 designed to grip 80 the cable 66 which is used for extricating stumps. Mounted on pivots 67 carried by the head 64 are two oppositely extending cam levers 68 which engage depressions 69 in the opposite faces of the jaws 65. The levers 68 extend through and work in slots 70 in the arms 61 and are provided at their outer end with holes 71 to enable suitable operating connections to be attached thereto. The connections referred to are not 90 shown but will extend to a point within convenient reach of the operator of the machine.

The cable 66 is wound upon a drum 72 normally loose on a drum shaft 73 extending transversely of the machine frame. Normally loose on the same shaft 73 is a second drum 74 designed to have what is known as the trip line wound thereon. The shaft 73 has a gear 75 thereon which is driven by a pinion 76 on a driving shaft 77 parallel to 100 the shaft 73 and driven from the countershaft 13 by means of a pinion 78 on said countershaft which meshes with and drives a gear 79 on the shaft 77.

The means for throwing the drums 72 110 and 74 into and out of operation, comprises in each case a fixed cam collar 80 surrounding the end portion of the shaft 73 and held rigidly by an arm 81 extending in one case, from one of the side bars 1 of the frame, 115 and in the other instance from an extension cross bar 82 of the frame. Between the cam collar 80 and the adjacent head of the drum there is positioned another collar 83 loose on the shaft 73, which, when turned in one direction by means of a lever arm 84 having a fixed relation to the collar 83, imparts a partial rotative movement of the collar 83 thereby pressing the adjacent drum toward the center of the machine where it engages a 125 clutch member 85 fast on the shaft 73. Any suitable manually controlled connections may be employed for operating the arms 84 of the cam collars 83. For the purpose of holding or anchoring the truck, the latter is 130

provided at one end thereof with draw bars 86 to which suitable anchoring chains or cables (not shown) may be fastened. Any suitable or preferred arrangement of steering mechanism may be employed to connect the steering knuckles 87 of the steering wheels with the steering shaft 88 having at its upper end the usual hand steering wheel 89.

- 10 From the foregoing description taken in connection with the accompanying drawings it will now be understood that the power of the engine is transmitted to the driving mechanism of the vehicle, for the 15 purpose of propelling the same to and from the point of operation. Upon reaching the point of operation, the engine and the vehicle driving mechanism may be uncoupled or disconnected and then the engine may be 20 coupled to the pump driving mechanism and also to the stump splitting and pulling or extricating mechanism. The compensation chamber prevents over pressure in the hydraulic cylinder, eliminating all danger 25 of filling the cylinder too full of water and thereby making it impossible for a careless operator to wreck the cylinder. This is due to the fact that the compensation chamber affords receiving space for the water or 30 other liquid displaced by the piston rod 43 in the inward movement thereof. By forcing water under pressure into the left hand end of the cylinder in Fig. 5, the piston 44 is driven to the right, thereby forcing the 35 splitting head 59 into or through the stump being operated upon. When the desired number of stumps have been split, the cable grip hereinabove described is fastened to the head 59 and then the cable 66 is secured 40 to a stump or to one or more of the split portions thereof and when the piston 44 is driven to the left in Fig. 5, the stump is extricated by the hydraulic pressure in the cylinder 36'. The cable in connection with 45 the operating mechanism therefor is also to be used in moving and piling logs, trees and stumps.

I claim:—

1. In a hydraulic stump splitter and 50 puller, the combination of a truck, traction and steering wheels supporting the truck frame, an engine mounted on the truck frame, clutch controlled driving mechanism between said engine and the traction wheels,

a hydraulic cylinder extending lengthwise 55 of the truck frame and supported thereby, a piston in said cylinder, a piston rod actuated by said piston, a pump, pipes connecting said pump with opposite heads of the hydraulic cylinder, a two-way valve controlling said pipes, a compensation chamber in communication with one end of said hydraulic cylinder, a stump splitting head carried by said piston rod, a cable holding drum, means for throwing said drum into 60 and out of operation, driving means between the engine and said drum, a cable grip detachably secured to said stump splitting head, said cable grip comprising oppositely arranged arms secured at one end to 65 the stump splitting head, a yoke connecting the opposite ends of said arms, a head, cable gripping jaws movably supported in said head, and oppositely arranged cam levers journaled in said head and arranged in co-operative relation to said jaws, the arms of 70 the grip being slotted to admit of the swinging movement of said cam levers.

2. In a hydraulic stump splitter and puller, the combination of a truck, traction 80 and steering wheels supporting the truck frame, an engine mounted on the truck frame, clutch controlled driving mechanism between said engine and the traction wheels, a hydraulic cylinder extending lengthwise 85 of the truck frame and supported thereby, a piston in said cylinder, a piston rod actuated by said piston, a pump, pipes connecting said pump with opposite heads of the hydraulic cylinder, a two-way valve controlling said pipes, a compensation chamber in communication with one end of said hydraulic cylinder, a stump splitting head carried by said piston rod, a cable holding drum, means for throwing said drum into 90 and out of operation, driving means between the engine and said drum, a cable grip detachably secured to said stump splitting head, said cable grip comprising oppositely arranged arms secured at one end to the 95 stump splitting head, a yoke connecting the opposite ends of said arms, a head, cable gripping jaws movably supported in said head, and levers pivoted in said head and arranged in co-operative relation to said 100 jaws.

In testimony whereof I affix my signature,
HOMER J. DANA.
